UNITED STATES PATENT OFFICE.

D. G. WELLS, OF NEW YORK, N. Y.

STEAM-GAGE.

Specification of Letters Patent No. 17,988, dated August 11, 1857.

To all whom it may concern:

Be it known that I, D. G. WELLS, of the city, county, and State of New York, have invented a new and useful Improvement in 5 Steam-Gages; and I do hereby declare that the following is a full and exact description of the same in all its essential parts.

The general features of this instrument consist of a case with a circular dial and 10 index all in the usual form. The pressure to be measured or indicated is applied within a flattened elastic tube which is placed within the case and which is folded together so as to present a series of layers 15 of the tube, each layer operating against the succeeding layer in such a manner that the final layer or closed end of the tube will have a motion proportionate to the number of layers used. The motion thus obtained is transmitted through a toothed sector and pinion shaft to an index which 20 moves over a graduated arc on the dial.

In order to explain my improvement more fully reference is had to the annexed drawings.

Figure 1 is a front view with the dial removed to show the parts more distinctly. Fig. 2, is a sectional side elevation, like letters referring to like parts.

30 A is the flattened tube with the layers *a, b, c, d, e*, bearing one upon the other, and having their point of contact at or near the center of each layer. The upper end of the tube is closed but there is a continuous passage through all the layers of the tube which communicates with a steam boiler or other vessel, through the socket B and pipe C. The motion of the upper layer *e*, is 35 transmitted to the index E, through the segment arm F, and pinion shaft G, which multiplies its range of motion in order to 40 make the indications more distinct on the dial D.

The coil spring I is attached one end to 45 the pinion shaft, and the other end to the stationary frame K, and serves to take up all the lateral play of the moving parts, and also keeps the projection H, of the arm F, pressing down upon the tube.

Fig. 3 is a lateral section of the tube on 50 a line through its center and shows the continuous passages through all the layers of the tube. Fig. 4, is a transverse section of the same on a line through the center of the socket B, and shows the flat sides of the tube 55 to be much thinner than the curved part or edges thereof. The object of this uneven thickness in the transverse section of the tube is to allow the flat part to yield more readily to the pressure while the 60 edges being much thicker are prevented from yielding beyond their limit of elasticity.

When a pressure above that of the atmosphere is applied within the tube all the 65 flat surfaces become curved outwardly which gives an upward movement to the layer *e*, and the index is thus carried forward over the graduated arc on the dial with a movement proportionate to the 70 degree of pressure applied.

The divisions of the arc are found by subjecting the instrument to various degrees of pressure in connection with a good mercurial gage. When a pressure below that 75 of the atmosphere is applied within the tube all the flat surfaces become curved inwardly which causes the index to move in the opposite direction and the instrument is then a vacuum gage, or it can be used as 80 a barometer by withdrawing the air from the interior of the tube and then closing it hermetically. The number of layers used will of course depend on the range of motion required for the final layer and can be 85 varied at pleasure, and the tube can be arranged to operate in any other position than that herein represented, as circumstances may require.

I claim—
The use of a flattened tube when constructed and arranged in layers substantially as herein described and for the purposes set forth.

D. G. WELLS.
